UNITED STATES PATENT OFFICE.

PINKNEY L. FRENCH, OF RUTHVEN, ALABAMA.

PORTABLE PLANING MILL.

Application filed June 7, 1923. Serial No. 644,039.

To all whom it may concern:

Be it known that I, PINKNEY L. FRENCH, a citizen of the United States, residing at Ruthven, in the county of Wilcox and State 5 of Alabama, have invented certain new and useful Improvements in Portable Planing Mills, of which the following is a specification.

This invention relates to portable planing 10 mills, and more particularly to a frame or mounting for planing mills which may be readily assembled and disassembled.

An object of the invention is the provision 15 of a planer mill support by means of which a mill may be readily transported from place to place where lumber is being cut, permitting the lumber to be dressed without transporting it to a distant planing mill.

A further object is to provide a support 20 for a planing mill consisting of a base, uprights or standards, and suitable transverse and inclined braces connecting the uprights above the base, said parts being formed of beams having notches formed therein for the 25 reception of the other members to be secured thereto, and being connected to each other by bolts or other suitable fastening elements.

In the accompanying drawings, I have 30 shown one embodiment of the invention. In this showing:

Figure 1 is a side elevation showing the planing mill in position on the support,

Figure 2 is a front elevation of the support,

Figure 3 is a detail perspective view of the base showing the adjacent ends of the parts connected thereto,

Figure 4 is a horizontal sectional view 40 on line 7—7 of Figure 2,

Figure 5 is a vertical sectional view on line 8—8 of Figure 1, and,

Figure 6 is a detail view of the upright and diagonal braces shown in Figure 5.

Referring to the drawings, the support 45 consists of a base or foundation formed of longitudinal runners 1. As shown, the lower face of the front end of the runners is cut away or inclined upwardly at the forward end, as indicated at 2, permitting the apparatus to be more readily loaded on a log wagon or other vehicle by means of which the mill is to be transported. The 50 runners are connected by transverse members 3. As shown, the upper faces of the runners are provided with recesses or

notches 4 in which the transverse members are arranged, as shown in Figure 8 of the drawings. The runners and transverse members are each provided with suitable openings 5 for the reception of bolts or other fastening elements. By providing the notches for the reception of the transverse members, a more rigid construction is produced and the parts of the foundation may 60 be more readily assembled as the transverse members may be easily arranged in proper position on the runners by placing them in the notches or recesses. The support is provided with a plurality of upright posts or 70 standards 6. As shown, the support is in the form of a rectangle in horizontal cross-section and is provided with four corner posts. These posts are received in notches or recesses 7 in the transverse members and 75 are secured to the transverse members by means of bolts passing through openings 8.

The front corner posts are connected by a transverse member 9, arranged intermediate the ends of the posts and are further 80 connected by a transverse member 10 arranged adjacent the top of the post. The upper ends of the standards on each side are connected by upper longitudinal members 11 which, as shown, project beyond the 85 corner posts. Suitable diagonal braces 12 are arranged between the projecting portions of the longitudinal members and the corner posts and the ends of these braces are received in notches or recesses 13 formed 90 in the posts and the longitudinal members.

The rear corner posts are connected by an upper transverse member 14 which is received in notches 15 in the corner posts. Transverse diagonal braces 16 are arranged 95 between the corner posts and the transverse member and are received in notches 17 in the sides of the corner posts.

A planer mill 18 is adapted to be arranged on the base or foundation. As the 100 planer mill may be of any construction, a detailed description thereof is deemed unnecessary. The mill is driven from a drive shaft 19, mounted in suitable bearings 20. As shown, the bearings are supported on 105 the front corner posts and are received in notches 21 formed therein. The drive shaft is provided with a pulley 23 adapted to receive a belt (not shown) connected to any suitable source of power. A second pulley 110 24 is mounted on the drive shaft and a belt 25 passes over this pulley and a pulley

26 mounted on a shaft 27. The shaft 27 is carried by the planer mill and is supported in bearings 28 on the front of the mill. When the device is assembled, the 5 end of the shaft may be supported in a bearing 29 carried by one of the front corner posts. This shaft is further provided with a pulley 30 adapted to receive a belt 31 which drives a shaft 32 on the bed of the 10 planer mill, the belt passing over a pulley 33 arranged on the shaft. The planer is provided with a suitable train of gears 34 by means of which the parts of the planer mill are driven in the usual manner. Suitable 15 suction pipes 35 and 36 are connected to a main duct 37. The ends of these pipes are provided with hoods 38 and 39 arranged above and below the bed of the planer and adapted to collect the shavings formed when 20 the planer is in operation. The end of the duct 37 is connected to a fan casing 40 having a fan (not shown) mounted therein. The fan is mounted on a shaft 41 which is supported in suitable bearings 42. These 25 bearings are mounted on a transverse member 43 arranged behind and adjacent the transverse member 14. The fan shaft is provided with a pulley 44 adapted to receive a belt 45 passing over a pulley 46 on the drive shaft 19. A shaft 47 is arranged at the rear of the machine, being supported in suitable bearings 48 mounted in notches 49 adjacent the rear ends of the upper longitudinal members 11. The shaft 47 is provided with a pulley 48 adapted to receive a belt 49, passing over a pulley 50, on the 30 main shaft. The shaft 47 is further provided with a pulley 51 by means of which power may be taken off for running other machinery.

Suitable means are provided for adjusting the tension of the belt 25 by means of which the planer mill is driven from the main shaft. As shown in Figure 4 of the 45 drawings, a pair of longitudinal members 52 are arranged on one side of the runners and connected to the transverse members 3. A shaft 53 is mounted on these longitudinal members and forms a pivotal support 50 for an arm 54. This arm is provided with an idler pulley 55 bearing against the belt

25. A lever 56 is pivotally mounted in one of the posts or standards and is connected to the arm 54 by means of a link 57.

It will be apparent that the entire support or frame may be readily disassembled for moving it from place to place and in assembling, the recesses in the beams and post permit the parts to be quickly placed in proper position. The recesses 49 further permit the shaft 47 to be readily arranged in its proper position. In transporting the mill, the superstructure may be removed from the base, the fan and blower conduits taken down and the planer mill 60 moved on the base or foundation. The runners 1 facilitate placing the mill on a log wagon or other conveyance for the purpose of transporting it to a desired place.

It is to be understood that the form of 70 the invention herewith shown and described is to be taken as a preferred example of the same, and that various changes in the shape, size, and arrangement of parts may be resorted to without departing from the spirit 75 of the invention or the scope of the subjoined claims.

I claim:

1. A support for portable planing mills comprising a pair of longitudinal runners, 80 transverse members connected to said runners forming a base, uprights connected to said transverse members, upper transverse and longitudinal members connected to said uprights, and diagonal bracing members 85 connecting said upper members to said uprights.

2. A support for planing mills comprising a pair of longitudinal runners, each of said runners being provided with a pair of 90 spaced notches, transverse members connected to said runners and arranged in said notches, each of said transverse members being provided with notches adjacent each end, upright members connected to said transverse members, and arranged in said notches, and upper transverse and longitudinal members connected to said uprights.

In testimony whereof, I affix my signature.

PINKNEY L. FRENCH.
